CLAIM

The ornamental design for a seat, as shown and described.

DESCRIPTION

FIG. 1 is a top, front, left perspective view of a seat, showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof; and,

FIG. 7 is a bottom plan view thereof.

The broken lines of even length shown in the drawings illustrate portions of the seat that form no part of the claimed design.
